UNITED STATES PATENT OFFICE.

BERNÁT GÁSPÁR, OF MISKOLCZ, AUSTRIA-HUNGARY.

RESTRAINING DEVICE.

1,183,396.

Specification of Letters Patent. Patented Apr. 20, 1915.

Application filed May 18, 1914. Serial No. 339,466.

To all whom it may concern:

Be it known that I, BERNÁT Gáspár, teacher of languages, subject of the King of Hungary, residing at 55 Széchenyi street, 5 Miskolc, in the county of Borsod and State of Austria-Hungary, have invented new and useful Improvements in Restraining Devices, of which the following is a specification.

10 The injury to health due to the practice of onanism or masturbation is so great that already various means have been devised to prevent persons of both sexes from committing such a crime against themselves. The 15 devices of this kind used heretofore, however, have not always proved successful.

The device, according to my invention, is so constructed as to absolutely prevent the person wearing the device from either manipulating his or her sexual organs, or in any other way exciting them by the movement of feet or legs, my new device being, moreover, conducive to quiet sleep.

My device consists of a shirt made of any 25 suitable or desired material, the sleeves of the shirt being sewed to the body of the shirt in such a way that the arms and hands of the person are forced to assume a position close to the body, from which position they 30 cannot be moved. The front of the shirt from the breast down to the feet or at least below the knees is made stiff or rigid so that the wearer can neither draw up the legs nor in any way move them nor lie on the 35 stomach, as in the latter case the rigid stiff portions of the shirt would create great discomfort or even pain.

In the drawing, in which I have illustrated my new device, by way of example, 40 Figure 1 is a front view of the shirt and Fig. 2 a partial cross-section along line 2—2 in Fig. 1.

The shirt *a* which may be of any suitable material is cut to closely fit the wearer. It 45 is open along its entire front and provided with button-holes *c* and buttons *b*. The sleeves *d* are fastened for some distance to the body of the shirt by a strong seam *e*.

The sleeves may be made of sufficient length to cover the hands. The front of the shirt 50 is made rigid by long stiffening pieces of which, as shown in the drawing, can reach from the breast down near to the bottom of the shirt, where the latter reaches the feet of the wearer. The stiffening parts can also 55 be made just long enough to reach below the knees, so as to make it impossible for the wearer to draw up the legs. These stiffening members may be made of wood, whalebone, or any other suitable material and of 60 any desired cross-section. They may be sewed in the material of the shirt, or simply sewed onto the shirt or otherwise fastened thereto. The shirt need not be open for its entire length, and, in place of buttons, other 65 fastening means can be used. The shirt must, of course, fit the body of the wearer closely so that the arms and hands can not be moved around in front.

I claim as my invention—

1. A shirt for preventing onanism comprising in combination with a close fitting body portion, longitudinal stiffening members extending along the front of the shirt, and sleeves sewed to the sides of said body 75 portion.

2. A shirt for preventing onanism comprising in combination with a close fitting body portion open in front, longitudinal stiffening members extending along both 80 sides of the open front, means for fastening the front, and sleeves sewed onto the sides of the said body portion.

3. A shirt for preventing onanism comprising a close fitting body portion, longitudinal stiffening members extending along the front of the shirt, and means for holding the arms in position on the sides of the 85 said body portion.

In testimony whereof I affix my signature 90 in the presence of two witnesses.

GÁSPÁR BERNÁT.
